COMBINATION BOOKRACK AND NOVELTY
DISPLAY STAND

Mansfield Royce Steidel, Arlington, Va.

Application July 17, 1956, Serial No. 42,283

Term of patent 14 years

(Cl. D33—2)

Fig. 1.

Fig. 3.

Fig. 2.

Fig. 1 is a perspective view of a combination bookrack and novelty display stand showing my new design;

Fig. 2 is a perspective view showing the rounded beveled ends of the combination bookrack and novelty display stand; and

Fig. 3 is a vertical section partly in elevation showing the arrangement of the supporting dowels and book retaining grill work.

I claim:

The ornamental design for a combination bookrack and novelty display stand, as shown.
